UNITED STATES PATENT OFFICE.

ELBA KENNETH MABRY, OF HOLDENVILLE, OKLAHOMA, ASSIGNOR OF ONE-THIRD TO
JOHN W. GILLAND, OF HOLDENVILLE, OKLAHOMA.

COLLAR-FASTENING.

1,186,925.

Specification of Letters Patent. Patented June 13, 1916.

Application filed April 22, 1915. Serial No. 23,196.

To all whom it may concern:

Be it known that I, ELBA K. MABRY, a citizen of the United States, residing at Holdenville, in the county of Hughes and 5 State of Oklahoma, have invented certain new and useful Improvements in Collar-Fastenings, of which the following is a specification.

The invention relates to fastening means 10 for securing the back of a collar to the neck band of a shirt or like article of wearing apparel without requiring the use of the ordinary collar button for such purpose which is objectionable because of the difficulty usually experienced in manipulating such button to secure or release the collar, and for the further reason that such button frequently exerts annoying pressure upon the back of the neck and prevents the free 15 sliding of the tie when adjusting and forming the same into a knot.

The invention consists of a fastening which may be applied to any variety of collar, said fastening embodying a clip and a 20 garment engaging member, the clip serving to secure the fastening to the collar and the garment engaging member being adapted to enter the pocket usually formed at the back 25 of a shirt band.

30 The invention, furthermore, consists of a fastening embodying a clip having a projection upon the inner side of one of the gripping members to enter the button hole at the back of the collar or to grip such 35 collar in a manner to prevent possible slipping of the fastening, the closed end of the clip being of such form as to comfortably receive the lower edge of the collar without 40 interfering with the gripping action of the elements of the clip.

With these and other objects in view, which will readily appear as the nature of the invention is better understood, the same 45 consists in the improved construction and novel arrangement and combination of parts which will be hereinafter fully described and particularly claimed.

In the accompanying drawing has been 50 illustrated a simple and preferred form of the invention, it being, however, understood that no limitation is necessarily made to the precise structural details therein exhibited, but that changes, alterations and modifications within the scope of the invention as 55 claimed may be resorted to when desired.

Referring to the drawing.—Figure 1 is a perspective view of a collar provided with a fastening embodying the invention; Fig. 2 is a section on the line 2—2 of Fig. 1; Fig. 3 is a sectional view of a modified form of 60 fastening; Fig. 4 is a similar view of a further modification.

Corresponding and like parts are referred to in the following description and indicated in all the views of the drawing by the same 65 reference characters.

The fastening is adapted to be applied to collars of different styles whether of the lay down or standing variety. In its general form the fastening embodies a clip and a 70 garment engaging member, the several parts being preferably formed of a single piece of sheet material bent into the shape required. The fastening shown in Figs. 1 and 2 comprises a clip embodying members 1 and 2 of 75 different lengths, the member 2 being of less length than the member 1 and adapted to extend along the inner face of the collar. The garment engaging member 3 projects from the clip member 2 about in line therewith and is spaced from the inner face of the collar so as to facilitate its engagement with the garment to which the collar is to be attached. The upper edge of the garment 80 engaging member 3 is provided with an integral upstanding extension or tab 3', the end walls of which are inclined downwardly and gradually merge into the upper edge of the member 3, said extension or tab constituting a pilot and facilitating the introduction of the tab within the pocket of the neck band of a shirt. A projection 4 extends from the member 2 toward the member 1 so as to enter the button hole of the 85 collar or to positively grip the same a short 90 distance from the lower edge of the collar, thereby preventing casual displacement of the fastening when properly positioned upon the collar.

In the form of fastening shown in Fig. 3 100 of the drawing, the clip comprises members 1^c and 2^c and a garment engaging member 3^c, the latter being offset with respect to the member 2^c. A projection 4^c is disposed to overhang the member 2^c and is located at the juncture of the members 2^c and 3^c. The projection 4^c serves to positively engage the collar as also to space the member 3^c from the collar to facilitate its ready engagement 105 with the pocket of the shirt band or with 110

the part of the garment to which the collar is to be attached.

The fastening illustrated in Fig. 4 comprises a clip embodying gripping members 5 1st and 2nd and a garment engaging member 3rd which is in line with the member 2nd. The gripping members of the clip are formed with inner projections 4th which are adapted to positively grip opposite sides of the collar so as to hold the fastening in place thereon.

The fastening herein disclosed may be constructed of sheet material which may be bent into any desired shape and which may 15 be attached to any style of collar since the clip forms convenient means for securing the fastening to the collar. The fastening admits of the collar being placed in position about the neck of the wearer and attached to the garment at one operation since the member projecting from the clip may be engaged with the garment at the same 20 operation and movement required to place the collar in position. It is obvious that the 25 collar may be removed and unfastened at a single operation since withdrawal of the collar from about the neck may be effected at the same time that the engaging member is released from the garment. The fastening is of such a nature as to lie close against 30 the face of the collar receiving the tie, hence offers no obstruction to the free sliding movement of the tie when adjusting the same in the formation of the knot. The 35 projections of the clip members insure firm gripping action of the clip and prevent casual displacement of the fastening after the latter has been placed in position upon the collar.

40 Having thus described the invention, what is claimed as new is:—

1. A collar fastener comprising a clip having gripping members adapted to embrace opposite sides of a collar and insertible 45 thereon from below by a sliding movement,

one of the gripping members being offset throughout a portion of its length and extended in the same general direction as said members to form an attaching tab for insertion into the pocket of a neck-band. 50

2. A collar fastener comprising a clip having gripping members adapted to embrace opposite sides of a collar and insertible thereon from below by a sliding movement, one of the gripping members having a projection extending inwardly toward the opposite gripping member for contact with a collar or insertion in the buttonhole thereof, that portion of one of the gripping members above the projection being offset and extended substantially parallel to the other gripping member to form an attaching tab for insertion into the pocket of a neck-band. 55

3. A collar fastener comprising a clip adapted to embrace the lower edge of a collar and including resilient gripping members, the free end of one of which is provided with a reduced extension constituting an attaching tab for insertion into the pocket of a neck-band, the side edges of the 60 tab being inclined downwardly and gradually merged into the adjacent gripping member, said fastener being held in position on the collar by frictional engagement therewith and having the ends of the tab 65 and clip extending in the same direction.

4. A collar fastener comprising a collar engaging clip having co-acting gripping members and an attaching tab projecting from the clip in the same general direction 70 as the gripping members and offset therefrom to enter a pocket formed in the neck-band of a shirt.

In testimony whereof I affix my signature in presence of two witnesses.

ELBA KENNETH MABRY. [L. S.]
